UNITED STATES PATENT OFFICE.

FOREST H. ANDERSON AND ELMORE McCLINTON, OF CLARKSVILLE, TEXAS.

MATTRESS.

1,208,889.

Specification of Letters Patent. Patented Dec. 19, 1916.

Application filed October 6, 1916. Serial No. 124,173.

To all whom it may concern:

Be it known that we, FOREST H. ANDERSON and ELMORE McCLINTON, citizens of the United States, residing at Clarksville, in the 5 county of Red River and State of Texas, have invented new and useful Improvements in Mattresses, of which the following is a specification.

This invention relates to mattresses and 10 more particularly the pattern of the blank from which the casing is made and it consists in the novel features hereinafter described and claimed.

An object of the invention is to provide 15 a mattress of simple and durable structure and of a pliable nature. One which will lie flat upon a bed spring or other approximately horizontal support and one which may be readily rolled or folded when not in 20 use.

The blank of the casing comprises a single piece of material having a broad end portion which is equivalent in length to the length of the mattress. The said broad end 25 portion is provided at its opposite side with incisions leading in at right angles to the edges thereof and which terminate at their inner ends in alinement with the edges of the narrow portion of the blank. When the 30 blank is formed up the narrower portion is extended over the broad portion and the edges of the narrow portion are secured to the edges of the broad portion and along the said incisions after the material between 35 the said incisions has been bent up approximately at a right angle to a plane in which the intermediate part of the broad portion lies.

In the accompanying drawing:—Figure 1 40 is a plan view of the blank from which the mattress is formed. Figures 2, 3, and 4 are detailed views of the features of the mattress.

The blank from which the mattress casing is formed is shown in plan in Fig. 1 and the said blank includes a relatively broad portion 1 and a relatively narrow portion 2. The broad portion 1 is of the same length as that of the mattress and the narrow portion 50 2 is somewhat longer than the broad portion 1. The portion 1 is provided at its side edges with incisions 3 which extend into the material at right angles to the edges of the said broad portion and the inner ends of the said incisions terminate in lines which

lie in alinement with the side edges of the narrow portion 2.

When the body of the mattress is formed up the material between the incisions 3 is bent up at right angles to the plane of the 60 body portion of the broader part 1 and the narrow portion 2 is extended over the said broad portion 1. In order to facilitate the description of the structure the material which lies between the incisions is referred 65 to as the tongues. When the narrow portion 2 is extended over the broad portion 1, the edges of the narrow portion 2 which are adjacent the edges of the innermost tongues 4 are sewed to the edges of the tongue 70 thereby providing a pocket which is filled with a suitable stuffing 5 of hair, cotton or other appropriate material. As each succeeding pocket is filled with the material, a line of stitching is run as at 6 through the 75 narrow portion 2 and the broad portion 1 whereby the narrow portion 2 is secured to the broad portion 1 and the material in the pocket is effectually confined. This method of attaching the parts is observed through- 80 all of the tongues 4 whereby the said tongues eventually constitute the end walls of the pockets which retain the stuffing material. The extreme outer edge of the nar- 85 row portion 2 is secured to the extreme outer edge of the broad portion 1 and thus the structure of the mattress is completed. Thus it will be seen that when the mattress is completed it is composed of a series of sec- 90 tions and double walls of the casing mate- 95 rial are interposed between the said sec- tions and the said double walls are secured at their bends or folds to the intermediate portion of the broad part 1 of the mattress blank. Furthermore it will be seen that in the formation of the casing all of the mate- 100 rial of the blank is utilized and there is no waste inasmuch as the incisions 3 are at true right angles to the longer edges of the broad portion 1 of the blank. Again it will be ob- 105 served that the mattress sections are rectan- gular in transverse section and consequently they fit squarely against each other at their adjacent side and render the mattress smooth and level when it is placed upon a bed spring or other approximately horizontal support.

Having described the invention what is claimed is:—

A mattress comprising a blank of a single piece of material, said blank having a broad 110

end portion and a narrow end portion, the broad end portion being equal in length to the length of the mattress, the said broad end portion having at its opposite side incisions leading in from its edges and terminating at their inner ends in lines which lie in alinement with the longer edges of the narrow portion, said incisions being disposed at right angles to the longer edges of the broad portion, the material between the said incisions constituting tongues which are bent up at right angles to the intermediate part of the broad portion and the narrow portion being extended over the broad portion and

secured at its edges to the edges of the said tongues and stitching passing through the narrower portion and the broad portion at the inner ends of the tongues and extending transversely across the broad portion and filling material located in the compartments thus formed between the narrow and broad portion and between the tongues at the opposite sides of the broad portion.

In testimony whereof we affix our signatures.

FOREST H. ANDERSON.
ELMORE McCLINTON.
